ATTORNEY.

UNITED STATES PATENT OFFICE.

LEE W. KENNARD, OF OMAHA, NEBRASKA.

SHIPPING-CASE.

1,356,453.

Specification of Letters Patent. Patented Oct. 19, 1920.

Application filed March 1, 1919. Serial No. 280,051.

To all whom it may concern:

Be it known that I, LEE W. KENNARD, a citizen of the United States, residing at Omaha, in the county of Douglas and State 5 of Nebraska, have invented new and useful Improvements in Shipping-Cases, of which the following is a specification.

This invention relates to a novel construction of shipping cases, and the principal 10 object of the invention is to provide means whereby glass and other fragile material may be carried from place to place without being broken.

Another object of the invention is to provide 15 means whereby the case may be used over and over again.

The invention also consists in certain other features of construction and in the combination and arrangement of the several 20 parts, to be hereinafter fully described, illustrated in the accompanying drawings and specifically pointed out in the appended claim.

In describing my invention in detail, reference will be had to the accompanying 25 drawings wherein like characters denote like or corresponding parts throughout the several views, and in which:—

Figure 1 is a top view of the invention; 30 and

Fig. 2 is a cross section on line 2—2 of Fig. 1.

In these views 1 indicates the case which consists of the side and end walls and the 35 bottom. The bottom is provided with a lining 2 made of canvas or the like and if desired, this lining may be carried up over the interior walls of the case. 3 indicates the top of the case which is composed of 40 two sections and each section is hinged to the end of the case by the hinges 4. The free ends of the section meet at the center of the case. The sections have secured to their inner faces coiled springs 5 which have 45 their free ends extending downwardly into the interior of the case when the sections

are in closed position. Thus when the plates of glass such as shown at 6, are placed in the case and the sections closed the said plates will be held against movement by 50 said springs. The lining will also act to protect the plates of glass against breakage. The means for holding the two parts of the cover in closed position consist of a plurality of bolts 7 carried by the sides of 55 the case and having their ends projecting above the top thereof and adapted to register with holes formed in the side edges of the sections. Thumb nuts 8 are adapted to engage with said bolts to clamp the sections 60 in closed position. It will be seen that when the thumb nuts are tightened the springs 5 will be pressed against the glass in the box and prevent movement of the same.

It is thought from the foregoing description 65 that the advantages and novel features of my invention will be readily apparent.

I desire it to be understood that I may make changes in the construction and in the combination and arrangement of the 70 several parts, provided that such changes fall within the scope of the appended claim.

What I claim is:—

A shipping case for plate glass including a bottom, side and end walls, a pair of cover 75 sections hinged at their outer ends to the end walls of the casing and having their inner ends arranged in opposed relation, a lining secured to the walls of the casing, a plurality of coil springs secured to the inner sides of said cover sections and adapted 80 to engage the plate glass within the casing to secure the same against movement, and a plurality of spaced fastening bolts extending through said bottom, side walls and cover sections for detachably locking said cover sections and for rigidly connecting the side walls to said bottom, said fastening bolts being provided with nuts. 85

In testimony whereof I affix my signature. 90

LEE W. KENNARD.
